CLAIM

The ornamental design for a cable receptacle, as shown and described.

DESCRIPTION

FIG. 1 is a left perspective view of a cable receptacle, showing my new design;

FIG. 2 is a right perspective view thereof;

FIG. 3 is a left side elevation view thereof; the right side elevation being a mirror image thereto;

FIG. 4 is a front elevation view thereof; the rear elevation being a mirror image thereto;

FIG. 5 is a top plan view thereof; and,

FIG. 6 is a bottom plan view thereof.

The broken line portion of the figure drawings is included to show unclaimed subject matter within the cable receptacle and forms no part of the claimed design.
